[57] **CLAIM**

The ornamental design for a toy water gun with extensible nozzle, as shown and described.

DESCRIPTION

FIG. 1 is a top plan view of a toy water gun with extensible nozzle showing my new design;

FIG. 2 is a bottom plan view thereof;

FIG. 3 is a side elevational view thereof;

FIG. 4 is a right end elevational view thereof;

FIG. 5 is a left end elevational view thereof;

FIG. 6 is a rear elevational view thereof;

FIG. 7 is another side elevational view thereof shown partially in fragment with the nozzle member in an extended position and the liquid container in a separated position.

FIG. 3
